SIDE CHAIR

Merle C. Melchior, Los Angeles, Calif., assignor of one-half to Sidney Galper, Los Angeles, Calif.

Original design application Sept. 29, 1964, Ser. No. 81,924, now Patent No. 203,437, dated Jan. 11, 1966. Divided and this application July 19, 1965, Ser. No. 86,984

Term of patent 14 years

(Cl. D15—1)

This application is a division of my co-pending application Serial No. D-81,924 filed September 29, 1964. Patent No. is 203,437.

I claim:

The ornamental design for a side chair, substantially as shown.
